BOTTLE OR THE LIKE CONTAINER HOLDER

Harold A. Shaver, Mount Rainier, Md.

Filed Jan. 10, 1963, Ser. No. 73,459

Term of patent 14 years

(Cl. D58—26)

FIG. I is a side elevational view of a bottle or the like container holder;

FIG. II is an elevational view taken from the right of FIG. I; and

FIG. III is a top plan view thereof.

My design comprises a notched cylindrical sleeve comprising an upright holder for an open bottle or the like, said sleeve being mounted upon a rectangular base having a tab at one end forming an extending bracket portion for securing the holder between the cushion and back of a vehicle seat, substantially as shown.

I claim:

The ornamental design for a bottle or the like container holder, as shown and described.
